UNITED STATES PATENT OFFICE.

SAMUEL MUND, OF ST. JOSEPH, MISSOURI, ASSIGNOR TO MAMIE E. MUND.

COMBINATION HAT CONFORMATOR, STRETCHER, &c.

SPECIFICATION forming part of Letters Patent No. 703,442, dated July 1, 1902.

Application filed October 25, 1901. Serial No. 79,955. (No model.)

To all whom it may concern:

Be it known that I, SAMUEL MUND, a citizen of the United States, and a resident of St. Joseph, Buchanan county, Missouri, have invented a certain new and useful Combination Hat Conformator, Stretcher, and Size-Measure, of which the following is a specification.

The object of my invention is to conform hats to the shape of the head, to adjust hats to the size of the head, and to measure hats from number six and five-eighths to the largest hat made.

Referring to the drawings, which form a part of this specification, Figure 1 is a diagram of the completed device looking at it from the top. Fig. 2 is a transverse section. Fig. 3 is a sectional detail. Fig. 4 is a sectional view of the racks and gear. Fig. 5 is a plan of the racks. Fig. 6 is a detail, and Fig. 7 a side elevation.

The rim or stretcher comprises six sections K, which abut against each other when contracted, but are not connected.

B and C represent six bars similar to each other. Each bar is attached at the outer end to a section or subdivision of the rim or block A and extends through and beyond the center of the device, and for a suitable distance on the inner side each bar is cogged. It will

be observed that the bars are arranged in pairs and that each member of each pair works freely upon each other member and the racks engage a cog-wheel 13', the center one bar on each side thereof, as shown in Fig.

5. In this connection we may refer to Fig. 4, which shows the center gear-wheels and the teeth on the bars. By turning the crank or key E the wheels below are turned. These

working in the racks on the bars increase or decrease the circumference of the device, thus stretching or relaxing the hat. The purpose of the two gears working upon the same axis may be explained as follows: The top wheel fits into the pair of bars that extend to the

45 sides of the device. This wheel fits loosely upon the axis, but may be made firm by the insertion of a key at the groove shown at letter M in Fig. 6. When the key is fitted in the groove, all the bars respond to the lever and

50 the hat is stretched evenly all around. When the key is removed, only the bars extending to the front and back of the hat respond. By this arrangement a hat may be made to fit a long or a wide head.

Fig. 6 represents the plate which covers the gear and connections in the center. One of these plates is placed above and another below the wheel, and they are bolted together by the bolts I in such a manner that they may be easily removed and the whole device taken to pieces.

Letter G (shown at Figs. 1, 3, and 7) is a small detached convex metal piece which fits the outer rim or block and may be placed at any position on the rim for the purpose of conforming the hat to irregular-shaped heads.

a, as shown at Fig. 1, is the inside or size ring. This ring, as shown by the drawings, is open and laps at the right side of the device. Upon this ring is indicated every size from a six and five-eighths hat to the largest hat made. As the hat is extended the ring expands, and where the two ends lap indicates the proper size, so that, the size having been ascertained, the hat may be increased to that size without removing the device.

In the very center of the device, as shown in Fig. 1, is a small notched wheel, with a key which fits into the notches. This enables the operator to retain the advantage gained by turning the crank or key.

Having now described my invention, what I claim as new, and desire to secure by Letters Patent, is—

1. A hat-stretching device comprising a ring composed of a plurality of independent sections, means for adjusting the sections radially, and convex pads secured to the outer periphery of said sections, substantially as described.

2. A hat-stretching device comprising a ring composed of a plurality of independent sections, a rack-bar connected to each section, said rack-bars being arranged in pairs extending across the center of the ring with the members of each pair slidably connected together, a gear-wheel between each pair of rack-bars engaging the teeth of both members, and means for operating said gears, substantially as described.

In witness whereof I have hereunto set my hand in presence of two witnesses.

SAMUEL MUND.
